US00D734434S

(12) **United States Design Patent**
Witkowski et al.

(10) **Patent No.:** **US D734,434 S**
(45) **Date of Patent:** **** Jul. 14, 2015**

(54) **SEAL ASSEMBLY**(71) Applicant: **S.P.M. Flow Control, Inc.**, Forth Worth, TX (US)(72) Inventors: **Brian Witkowski**, Weatherford, TX (US); **Nuder Said**, Fort Worth, TX (US)(73) Assignee: **S.P.M. Flow Control, Inc.**, Fort Worth, TX (US)(***) Term: **14 Years**(21) Appl. No.: **29/493,861**(22) Filed: **Jun. 13, 2014****Related U.S. Application Data**

(63) Continuation of application No. 29/449,852, filed on Mar. 15, 2013, now Pat. No. Des. 707,332.

(51) **LOC (10) Cl.** ..... **23-01**(52) **U.S. Cl.**USPC ..... **D23/249**(58) **Field of Classification Search**

Primary Examiner — Cynthia Ramirez(74) *Attorney, Agent, or Firm* — Gardere Wynne Sewell LLP(57) **CLAIM**

The ornamental design for a seal assembly, as shown and described.

DESCRIPTION

FIG. 1 is a front perspective view of a seal assembly; FIG. 2 is a top view of the seal assembly, the bottom view being a mirror image thereof;

FIG. 3 is a front elevation view of the seal assembly, the rear view being a mirror image thereof; and,

FIG. 4 is right side elevation view of the seal assembly, the left side being a mirror image thereof.

The broken lines in the figures are included for the purpose of illustrating environment and form no part of the claimed design.
